[57] CLAIM

The ornamental design for a telephone set, as shown and described.

DESCRIPTION

FIG. 1 is a front, top and right side perspective view of a telephone set in assembled position showing my new design;

FIGS. 2 and 3 are respectively top and bottom plan views thereof;

FIGS. 4 and 5 are respectively left and right side elevational views thereof;

FIGS. 6 and 7 are respectively front and rear elevational views thereof; and

FIG. 8 is a front, top and right side perspective view of the stand, and a front, top and partial view of the handset placed alongside the stand.

The cord is shown in abbreviated form in FIGS. 2, 4, 5, 6 and 7 for facility of illustration.
